(57) **CLAIM**

The ornamental design of a sound amplifier, as shown and described.

DESCRIPTION

FIG. 1 is a perspective view of sound amplifier in accordance with an embodiment of the present invention;

FIG. 2 is a front view of the sound amplifier of FIG. 1;

FIG. 3 is a rear view of the sound amplifier of FIG. 1;

FIG. 4 is a left side view of the sound amplifier of FIG. 1;

FIG. 5 is a right side view of the sound amplifier of FIG. 1;

FIG. 6 is a top plan view of the sound amplifier of FIG. 1;

FIG. 7 is a bottom plan view of the sound amplifier of FIG. 1;

FIG. 8 is a verticality section view of the sound amplifier of FIG. 2; and,

FIG. 9 is a view of using state of the sound amplifier of FIG. 1.

Broken lines are included herein for illustrative purposes only and form no part of the claimed design.
